[57] CLAIM

The ornamental design for octagonal syringe holder, as shown and described.

DESCRIPTION

FIG. 1 is a perspective view of an octagonal syringe holder as viewed from the front and side thereof;

FIG. 2 is an elevational view of one end of the octagonal syringe holder;

FIG. 3 is an elevational view of the opposite end of the octagonal syringe holder;

FIG. 4 is a top plan view of the octagonal syringe holder;

FIG. 5 is a bottom plan view of the octagonal syringe holder; and,

FIG. 6 is an elevational view of one side of the octagonal syringe holder, the opposite side being the mirror image thereof.
